LOUIS K. SCOTFORD, OF CHICAGO, ILLINOIS, ASSIGNOR TO HILL-INDEPENDENT MANUFACTURING CO., OF MUSKEGON, MICHIGAN, A CORPORATION OF ILLINOIS.

HAND-STAMP.

1,245,624.

Specification of Letters Patent.

Patented Nov. 6, 1917.

Application filed March 28, 1912. Serial No. 686,930.

To all whom it may concern:

Be it known that I, LOUIS K. SCOTFORD, a citizen of the United States of America, and a resident of Chicago, in the county of Cook and State of Illinois, have invented certain new and useful Improvements in Hand-Stamps, of which the following is a specification.

My invention relates to improvements in that class of hand stamps in which it is desirable to adjust or change part of the printing characters, and the object of the invention is to provide a stamp of this character which will be capable of ready adjustment and one which can be readily assembled and extremely durable in use.

The invention consists in the construction which is hereinafter more particularly described and illustrated, in its preferable embodiment, in the accompanying drawings.

Referring to the aforesaid drawings:

Figure 1 is a perspective view of a hand stamp made in accordance with my invention.

Fig. 2 is a side elevation of the same.

Fig. 3 is a vertical central section showing, in dotted lines, the parts thrown in position for adjustment.

Fig. 4 is a perspective view of a blank.

Fig. 5 is a perspective view of the frame made out of the blanks shown in Fig. 4 having the sheet metal frame or drum connected therewith.

Fig. 6 is a sectional view intended to show the spring catch.

Fig. 7 is a sectional detail.

Fig. 8 is a perspective view of the die plate detached.

Fig. 9 is a perspective view of the modified form.

Referring now to the details of the drawings by numerals: 1 designates the main frame of what is known as the "tumbler" form of hand stamp and, as usual, comprises a handle 2 for depressing the yoke 3 which is connected to the frame, hereinafter described, for supporting the printing characters 4. In the preferred embodiment of my invention, each of the side members of the frame 1 is provided with a slot 6 in which travels a lug 8 (Fig. 7) projecting at right angles from an arm 10 formed on or rigidly connected with the lower end of the yoke 3. It will be understood that these parts are

exactly alike on each side of the main frame 55. 1. It follows from the construction just described that whenever the handle 2 is depressed the yoke 3 is caused to travel in an absolutely vertical line owing to the fact that the lugs 8 slide within the vertical slots 60 6. As a modified construction, I have illustrated the yoke 3^a in Fig. 9, as having two arms 12 and 14 on opposite sides of the end of the yoke, these arms 12 and 14 having flanges 16 and 18 which embrace the vertical edges of the main frame 1^a in said figure and thus cause the yoke 3^a to travel in a vertical line without employing a slot 6 such as shown in Fig. 1. I consider this modified construction as equivalent to the construction shown in Fig. 1, although I prefer the form shown in Fig. 1 as being simpler.

Heretofore it has been common in hand stamps of this character to connect the ends of the yoke 3 with the frame carrying the die plate and the printing characters by means of a rod or cross bar which passes completely through the stamp, from one end of the yoke to the other end of the yoke 3, this construction being shown in my Patent No. 668,021. It has also been proposed to employ a common screw on each side of the frame to secure the end of each end of the yoke 3 to the die plate of the frame carried thereby. To avoid the use of both of these constructions, I employ the construction shown particularly in Figs. 1 and 7. As there shown it will be observed that I have employed a short stud 20 having an annular flange 21 near one end thereof. The end 22 of the stud 20 is inserted in an opening in part of the movable frame 26 and is riveted therein as clearly shown in Fig. 7, the annular flange 21 serving, when the parts are in use, to properly space the movable part of the frame 26 from the side of the main frame 1. The stud 20 will project through a grooved slot 28 in the side of the main frame 1 and will pass through a horizontally disposed slot 30 formed in the lower end of the yoke 3 and its arm 10, as seen in Figs. 1 and 7, a ring 32 being clamped in the groove 34 in the end of the stud 20 to hold the parts in position. In order to prevent undue friction, I prefer to place an anti-friction roller 33 around the stud 20, said roller projecting into the slot 30 of the arm 10, as illustrated in Fig. 7. It has hitherto been im-

possible to use any kind of a stud such as the one 20 in Fig. 7, for the reason that the parts could not be properly assembled. To make the assembling possible and easy, I 5 form the lower end of each side of the frame with an extension 36 having therein a continuation of the slot 28, this extension being bent at right angles to the side frame so that the slot in the extension is at right 10 angles to the slot in the side frame. This slot is just the proper size to permit the passage of the stud through it, and after the die plate with the studs thereon is slipped in position and the studs are above the flanged 15 extensions 36, the ends of the yoke 3 may be slipped over the ends of the studs, and the rings 32 may then be clamped in the grooves 34 of the studs and the various parts properly secured together. The flanges 40 and 20 42 projecting from the die plate 44 are slotted so that the sides of the flanges 40 and 42 straddle blocks 46 and 48 which are journaled on headed pins 50 and 52 secured to the side frames as shown in Fig. 2, (see 25 also Fig. 8). When the handle 2 and its yoke 3 are depressed so that the die plate 44 is caused to descend, the yoke, as before stated, is caused to descend in a vertical line owing to the fact that the end of its arm 10 30 fits within the vertical slot 6. At the same time, the studs 20 projecting from the flanges 40 and 42 of the die plate 44 are given a movement by the shape of the slots 28 which cause said studs to slide in the slots 30 of 35 the arms 10 at a time when the die plate is near the center of its movement. The result of this movement is that the flanges 40 and 42 of the die plate and their journaled blocks 46 and 48 are caused to partially rotate on 40 the headed pins 50 and 52 so that the die plate is caused to "tumble" from the inking to the printing position. By this tumbling movement the die plate is given a truly vertical movement both at the beginning and 45 end of its stroke owing to the fact that both ends of the grooved slot 28 are in a vertical line. Hence the die plate is given an absolutely vertical movement at the time the printing characters touch the inking pad 50 and also an absolutely vertical movement at the time the printing characters are in the act of printing.

The die plate 44 has two lugs 56 projecting therefrom and to these lugs is pivotally secured a frame 58 which I prefer to make of one piece of metal from a blank such as shown in Fig. 4. This blank is so manipulated that it is formed into the form shown in perspective view in Fig. 5 and as there 55 shown it has two side arms 59 and 60 which are pivotally connected to the lugs 56 projecting from the die plate 44. Rectangular portions 62 on opposite sides of the blank shown in Fig. 4 are formed to make tubular 60 posts 63 and 64 which are screw threaded

to receive screws 66 and 68, these screws adjustably securing a sheet metal form or drum 70 between the two arms 59 and 60 of the frame 58 as shown in Figs. 2 and 5. The member 71 of the blank shown in Fig. 4 forms the connecting web 72 shown in Fig. 5, and the projections 73 of Fig. 4 are bent downward to the position shown at 74 of Fig. 5 for the purpose of having secured to them a spring catch 80. This spring 7 catch has a resilient thumb piece 81 at one portion thereof and a locking flange 82 at the other end thereof, said flange being in just the proper position to lock over the flange 86 of the die plate 44 as indicated in Fig. 6. The construction is such that when the operator presses with his thumb or finger against the member 81, the flange 82 of the spring catch 80 is caused to move from the position shown in full lines to the position shown in dotted lines in Fig. 6 thus loosening the catch of the die plate and permitting the frame 58 with its form or drum 70 to be moved on the lugs 56 as a pivot. The form or drum 70 is for the purpose of supporting the printing characters 4 and nothing new is claimed in either the frame or the printing characters, they being very clearly shown in my Patent No. 668,021 of Feb. 12, 1901.

The die plate 44 is provided with a thin sheet metal plate 90 shown best in Fig. 6 having two flanges 91 adapted to hold the movable type in alinement.

The detailed description has been given in such detail that it is believed that a description of the operation is unnecessary.

It is obvious that changes and other modifications may be made besides the one shown in the drawings and reference should therefore be made to the accompanying claims to determine the scope of the invention.

What I claim as my invention is:

1. In a hand stamp, the combination of a frame having a straight portion and also having a slot with two straight portions connected by a curved portion, a handle, a yoke having a slot therein and a flange, the flange co-acting with a straight portion of the frame to compel the yoke to move in a straight line, a reversible die plate, and means passing through the slot in the yoke and the slot in the frame and connecting said yoke with said die plate, whereby when the handle and yoke are depressed, the means connecting the die plate with the handle moves in the slot having the straight and curved portions and at the same time moves in the slot in the yoke.

2. In a hand stamp, the combination of a frame having two slots therein one of which is straight and the other having two straight portions connected by a curved portion, a handle, a yoke having a slot therein and a member projecting within the straight slot

of the frame to compel the yoke to travel in a straight line, a reversible die plate and means passing through the slot in the yoke and the slot in the frame and connecting said yoke with said die plate whereby when the handle and yoke are depressed, the means connecting the die plate with the handle moves in the slot having the straight and curved portions and at the same time moves in the slot in the yoke.

3. In a hand stamp, the combination of a frame having two slots therein one being straight and the other having two straight portions connected by a curved portion, a handle, a yoke having a slot therein and an arm projecting therefrom having a flange projecting into the straight slot of the frame to compel the yoke to travel in a straight line, a reversible die plate, and means passing through the slot in the yoke and the slot in the frame and connecting said yoke with said die plate, whereby when the handle and yoke are depressed, the means connecting the die plate with the handle moves in the slot having the straight and curved portions and at the same time moves in the slot in the yoke.

4. In a hand stamp, the combination of a frame having two slots therein one being straight and the other having two straight portions connected by a curved portion, a handle, a yoke having a slot therein and an arm projecting therefrom having a flange projecting into the straight slot of the frame to compel the yoke to travel in a straight line, a reversible die plate having arms supported to travel and turn on a pivot adjacent to the curved portion of the aforesaid slot, and means passing through the slot in the yoke and the slot in the frame and connecting said yoke with said die plate, whereby when the handle and yoke are depressed, the means connecting the die plate with the handle moves in the slot having the straight and curved portions and at the same time moves in the slot in the yoke.

5. In a hand stamp, the combination of a frame having two slots therein one being straight and the other having two straight portions connected by a curved portion, a handle, a yoke having a slot therein and an arm projecting therefrom having a flange projecting into the straight slot of the frame to compel the yoke to travel in a straight line, a reversible die plate having side arms with a slot therein, a pin projecting from the frame adjacent to the curved portion of one of said slots, and within the slot in the arms of said reversible die plate, and means passing through the slot in the yoke and the slot in the frame and connecting said yoke with said die plate, whereby when the handle and yoke are depressed, the means connecting the die plate with the handle

moves in the slot having the straight and curved portions and at the same time moves in the slot in the yoke.

6. In a hand stamp, the combination of a slotted frame, a handle, a yoke, a reversible die plate, and a stud for connecting said die plate with said yoke, said stud being secured to the die plate and having a spacing flange projecting between the die plate and the slotted frame, the free end of the stud projecting through the slot in the frame and being connected with the end of the aforesaid yoke.

7. In a hand stamp, the combination of a frame having flanges projecting outwardly therefrom near the lower portions of the frame, said frame having slots therein extending into the flanges, a handle, a yoke, a reversible die plate, and studs projecting outwardly from said die plate through the slots in the side of said frame and into the ends of the yoke, the slotted flanges of the frame permitting said die plate to be assembled after the studs have been secured to the die plate.

8. In a hand stamp, the combination of a frame having flanges projecting outwardly therefrom near the lower portions of the frame, said frame having slots therein extending into the flanges, a handle, a yoke, a reversible die plate, and studs projecting outwardly from said die plate through the slots in the side of said frame and into the ends of the yoke, the slotted flanges of the frame permitting said die plate to be assembled after the studs have been secured to the die plate, said studs having flanges spacing the die plate from the sides of said frame.

9. In a hand stamp, the combination of a frame having flanges projecting outwardly therefrom near the lower portions of the frame, said frame having slots therein extending into the flanges, a handle, a yoke, a reversible die plate having side arms, and studs projecting outwardly from the arms of said die plate through the slots in the side of said frame and into the ends of the yoke, the slotted flanges of the frame permitting said die plate to be assembled after the studs have been secured to the die plate.

10. In a hand stamp, the combination of a frame having flanges projecting outwardly therefrom near the lower portions of the frame, said frame having slots therein extending into the flanges, a handle, a yoke, a reversible die plate having side arms, and studs projecting outwardly from the arms of said die plate through the slots in the side of said frame and into the ends of the yoke, the slotted flanges of the frame permitting said die plate to be assembled after the studs have been secured to the die plate, said studs having flanges spacing the die plate from the sides of said frame.

11. A hand stamp comprising two main parts, a die plate and a frame, said parts being pivoted to each other, and said frame being formed of one piece of sheet metal 5 having two side members pivotally connected to the aforesaid die plate and two posts or standards projecting from said side members, a form or drum carried by said posts or standards and supporting the printing 10 characters, and a spring catch carried by said sheet metal frame and adapted to engage the die plate to hold said parts in operative position.
12. In a hand stamp the combination of 15 a slotted frame, a handle, a yoke, a die plate, a stud for connecting said die plate with said yoke, said stud being secured to the die plate and having an integral spacing flange and its free end projecting through the 20 frame into said yoke, and an anti-friction roller on said stud.

13. In a hand stamp, the combination of a frame, a handle, a yoke, a reversible die plate provided with flanges, as 40 and 42,

projecting from said die plate and having 25 slots therein, and rectangular blocks journaled to the sides of said frame, the slotted flanges of the die plate being arranged to slide and turn upon said journaled blocks.

14. In a hand stamp, the combination of a 30 frame having a slot therein, a handle, a yoke, a reversible die plate provided with flanges, as 40 and 42, having slots therein, and rectangular blocks journaled to the sides of the frame adjacent to the aforesaid slots, the 35 slotted flanges of the die plate being arranged to slide and turn upon said rectangular blocks, the slot of the aforesaid frame being shaped to reverse the position of the die plate as the yoke moves with respect to 40 said frame.

In testimony whereof I affix my signature in presence of two witnesses.

LOUIS K. SCOTFORD.
